(57) **CLAIM**

The ornamental design for a transmission rear housing, as shown and described.

DESCRIPTION

FIG. 1 is a front perspective view of a first embodiment of our new design;

FIG. 2 is a rear perspective view of the new design;

FIG. 3 is another rear perspective view of the new design;

FIG. 4 is another front perspective view of the new design;

FIG. 5 is a front view of the new design;

FIG. 6 is a rear view of the new design;

FIG. 7 is a first side view of the new design;

FIG. 8 is a second side view of the new design;

FIG. 9 is a third side view of the new design;

FIG. 10 is a fourth side view of the new design;

FIG. 11 is a front perspective view of a second embodiment thereof;

FIG. 12 is a rear perspective view thereof;

FIG. 13 is a front view thereof;

FIG. 14 is a rear view thereof;

FIG. 15 is a first side view thereof;

FIG. 16 is a second side view thereof;

FIG. 17 is a third side view thereof;

FIG. 18 is a fourth side view thereof;

FIG. 19 is a rear perspective view of a third embodiment thereof;

FIG. 20 is a rear view thereof;

FIG. 21 is a front view thereof;

FIG. 22 is a first side view thereof;

FIG. 23 is a second side view thereof;

FIG. 24 is a third side view thereof; and,

FIG. 25 is a fourth side view thereof.

The broken lines in FIGS. 1-25 depict portions of the transmission rear housing which form no part of the claimed design.
